[57] CLAIM

The ornamental design housing for a portable communications device, as shown and described.

DESCRIPTION

FIG. 1 is an isometric view of a portable communications device showing our new design;

FIG. 2 is a front elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a back elevational view thereof.

The broken lines encompassing the two unshaded circular areas at the top in FIGS. 1 and 5 define, but are not included in, portions of the article which form no part of the claimed design.
